UNITED STATES PATENT OFFICE.

WILLIAM M. MIXER, OF NEW YORK, N. Y.

ICE-MACHINE.

SPECIFICATION forming part of Letters Patent No. 290,911, dated December 25, 1883.

Application filed October 2, 1883. (No model.)

To all whom it may concern:

Be it known that I, WILLIAM M. MIXER, a citizen of the United States, and a resident of the city, county, and State of New York, have 5 invented certain new and useful Improvements in Ice-Machines, of which the following is a specification.

My invention relates to that class of ice-machines which use compression-pumps for 10 condensing the refrigerant, and known as "compression-machines," and it consists in the arrangement of the engine, compressing-cylinders, and intermediate parts, as fully described hereinafter, so as to simplify the construction, reduce the number of parts and 15 amount of space occupied, and avoid the friction and loss of power incident to ordinary constructions.

My invention further consists in a peculiarly 20 constructed valve arrangement, and in certain details, hereinafter fully set forth.

In the drawings, Figure 1 is a perspective view of sufficient of the compression-cylinders and steam-engine to illustrate my invention. 25 Fig. 2 is an elevation enlarged, in section through the vertical compression-cylinders and their supports and connections. Fig. 3 is a side elevation in part section of a vertical compression-cylinder, supporting-frame, and piston-operating appliances. Fig. 4 is a section 30 of one leg of the frame on the line 1 2, Fig. 3, showing its tubular form. Fig. 5 is a detached view in section of one of the compression-cylinders and valve-chest and valves; 35 Fig. 6, a detached view of a valve-chest with side caps removed; Fig. 7, an elevation in part section of one of the compression-cylinders; Fig. 8, a plan of the compression-cylinders, the valve-chest in section.

40 The frame of the apparatus is constructed in any suitable manner to support the cylinder A of a steam-engine, the bearings C C, for the straight shaft B of the engine, and two vertical compression-cylinders, D D', each of which 45 is single-acting, pumping on the upstroke, and is provided with a piston, E, piston-rod F, and connecting-rod G. One of the connecting-rods engages with a wrist-pin, a, projecting from a crank wheel or disk, H, upon one end of the 50 shaft B, and the other connecting-rod is connected to a wrist-pin, b, of a crank wheel or

disk, I, upon the opposite end of the shaft B. To the wrist-pin b is also connected the end of the connecting-rod J of the steam-engine, the valve of which is operated by the usual 55 rod and appliances from eccentrics c, upon the shaft B, which also carries a fly-wheel, d.

By the arrangement above described, reciprocating motions are imparted to the pistons E E from the engine without the use of the 60 double cranks, drag-cranks, double wheels, and forked rods heretofore employed, whereby I avoid not only the expense incident to the construction of such parts, but also largely reduce the space occupied by the machine, and 65 dispense with a multiplicity of pillow-blocks and bearings, which are expensive, difficult to keep in line, and result in much friction and loss of power.

To secure greater strength and steadiness 70 with reduced weight of material, I construct each of the upright frames K, which support the cylinders D D' and the guides e, of cast metal, with tubular converging side pieces or columns, f f, flanged at the lower ends and 75 bolted to the bed-frames G and connected by the web g, to which the guides e are secured, being in some instances cast therewith.

To the upper ends of the frames K is bolted the platform L, which surrounds the cylinders 80 D D'. The lower head of each compression-cylinder is provided with a suitable packing-box is dished to constitute a receptacle for oil which may be forced past the piston by the excessive pressure above the latter, and 85 provided with a port or pipe, h, which extends inward to a considerable extent, as shown in Fig. 7, so as to maintain a body of oil around the piston-rod within the cylinder, but permit a free discharge of any surplus oil which 90 would collect above the line x x, Fig. 7. A vent-pipe, i, communicates with the channel or pipe h and conducts the oil to a suitable receptacle. An annular flange, j, projects inward from the head k around the piston-rod, 95 and serves to scrape off from the latter any matter which would otherwise adhere thereto, thereby tending to prevent the wearing away of the packing and leakage around the rod. Each valve-chest M is provided with a central 100 chamber, m, communicating laterally with a port, n, at the upper end of the cylinder, and

at the lower end with a suction-pipe, N, for the incoming refrigerant, and the upper end with a pipe, P, through which the gas is forced outward under pressure. The chamber *m* communicates with the lower port, *p*, through an oblong port or opening, *s*, in a raised valve-seat, *t*, and with the upper port, *q*, through an oblong port, *s'*, in a raised valve-seat, *t'*, extending into the chamber *m'*.

10. In the opposite sides of the chambers *m m'* are vertical slots *y y*, into which extend the ends of rectangular blocks *Q*, which rest upon the valve-seats *t t'*, and constitute the valves. The blocks *Q* may be held upon the seats by their own weight or under the pressure of suitable springs, and may consist of wood, compressed pulp, metal, or any suitable material or composition. The valves thus constructed and arranged rise freely and with little or no friction, close quickly, wear evenly, and may be readily fitted to their seats and easily removed and replaced.

15. To facilitate the adjustment or removal of the valves, the slots *y y* are made through the sides of the chest *M* and are closed by caps *u*, so bolted externally to said sides as to be readily detached and connected. The valves may, however, be differently located. One may be placed on the side and one on the top of the 20 compression-cylinder, or they may be both placed on the top.

25. As the operation of the machine thus constructed will be obvious to those familiar with the art, it will be unnecessary to describe it here further than to state that the descent of the piston *E* draws the refrigerant through the ports *p s n* and chamber *m*, lifting the lower valve, *Q*, and the ascent of the piston forces the gas through the ports *n s' q* and 30 chambers *m m'* into the pressure-pipe, lifting the upper valve. Where the machine is small, it may be driven by a belt from a driving-shaft, the belt passing to a pulley on the shaft *B*.

I claim—

40. 1. The combination, in an ice-machine, of a horizontal engine, a straight shaft provided with cranks or crank-wheels at opposite ends, and vertical compressor-cylinders arranged above said cranks, with their connecting-rods working on the wrist-pins thereof, the connecting-rod of the engine being also connected to one 45 of said wrist-pins, substantially as set forth.

50. 2. The combination, in an ice-machine, of

a frame supporting inverted vertical compressor-cylinders and a driving shaft arranged in bearings below said cylinders, having a fly-wheel attached thereto between said bearings, and provided with cranks or crank-disks at the ends connected to the rods of the cylinders, substantially as described. 55

3. The frames *K*, supporting the upright cylinders, consisting each of tubular converging side pieces and a connecting-web, substantially as set forth. 65

4. The inverted compression-cylinder provided with an oil-discharge pipe or port extending from the lower dished head inward, substantially as specified.

5. The compression-cylinder provided with 70 a dished head at the lower end, having an inwardly-projecting annular flange, *J*, around the piston-rod, for the purpose set forth.

6. The compression-cylinder provided with an inlet and outlet port or ports, *n*, and with 75 a valve-chest, *M*, having chambers *m m'*, valve-seats, and ports *p s s' q*, and rectangular block-valves extending into vertical slots in the sides of the chest, substantially as set forth.

7. The valve-chest *M*, connected to the cylinder *D*, having inlet and outlet ports at its opposite ends, valve-seats, and block-valves *Q*, extending into slots in the sides of the chest covered by caps *u*, substantially as specified. 80

8. The combination, in a pumping-engine, 85 of a revolving shaft provided with a fly-wheel intermediate between two pillow-blocks, and with cranks at the ends of the shaft exterior to said pillow-blocks, and with two pumping-cylinders—one connected to each of said 90 cranks—and of an engine connected likewise to one of said cranks, substantially as described.

9. The combination, in a pumping-engine, 95 of an engine, a straight shaft provided with cranks or crank-wheels at opposite ends, and vertical compressor-cylinders arranged above said cranks, with their connecting-rods working on the wrist-pins thereof, the connecting-rod of the engine being also connected to one of said wrist-pins, substantially as set forth. 100

In testimony whereof I have signed my name to this specification in the presence of two subscribing witnesses.

WILLIAM M. MIXER.
